UNITED STATES PATENT OFFICE.

PETER G. VAN WIE, OF HAMILTON, OHIO, ASSIGNOR TO F. & L. KAHN & BROS., OF SAME PLACE.

WATER-HEATER.

SPECIFICATION forming part of Letters Patent No. 638,301, dated December 5, 1899.

Application filed January 16, 1899. Serial No. 702,214. (No model.)

To all whom it may concern:

Be it known that I, PETER G. VAN WIE, a citizen of the United States, and a resident of Hamilton, Butler county, Ohio, have invented 5 certain new and useful Improvements in Water-Heaters, of which the following is a specification.

This invention pertains to improvements in water-heaters, and the improvements will be 10 readily understood from the following description, taken in connection with the accompanying drawings, in which—

Figure 1 is a vertical section of a water-heater embodying my improvements; Fig. 2, 15 a vertical section of the upper portion of the heating-screw, and Fig. 3 a side elevation of the heater shown as provided with a supporting-bracket instead of a supporting-base.

In the drawings, 1 indicates a large and very 20 coarse-threaded screw; 2, the hollow or tubular body of the screw; 3, the hollow thread of the screw, the same being illustrated as of bastard section and abnormally thin—that is to say, the spaces between the threads are 25 greater in thickness than the threads themselves; 4, a tube disposed within the hollow body of the screw and secured thereto watertight by threads at each end, this tube forming a core within the screw; 5, the hollows of 30 the threads of the screw, their interior walls being formed by tube 4; 6, a spiral rib formed upon the inner surface of screw-body 2 and engaging the periphery of tube 4, the bore of screw-body 2 being larger than the exterior of 35 tube 4, so as to make room for this rib; 7, a thin space formed between the inner wall of screw-body 2 and the outer surface of tube 4 above and below rib 6, this space following the spiral of the screw and forming upper 40 and lower thin extensions of the hollow 5 of the screw-thread; 8, the hot-water outlet in the form of a pipe screwed horizontally into the upper end of the heating-screw, so as to be in communication with the upper terminal 45 of the hollow 5 of the thread; 9, the cold-water inlet correspondingly arranged at the lower terminal of the screw-thread; 10, a cylindrical metallic jacket inclosing the heating-screw and fitting the exterior of its thread;

50 this jacket being formed, preferably, of two thicknesses of sheet metal; 11, a thickness of

insulating material, as asbestos, disposed between the two layers of the metallic jacket; 12, the spiral heat - passage formed by the spaces between the screw-threads and having 55 its outer wall formed by the jacket; 13, a base forming a finish for the lower end of the jacket and forming also a receptacle and support for the burner-work; 14, legwork, which may, if desired, be added to the base to support the 60 structure free of the floor if it is to be employed as a standing heater resting on the floor; 15, an ordinary ring gas-burner disposed within the base and arranged to discharge its heated products upwardly into the 65 casing around the body of the screw; 16, a tubular gas-burner extending upwardly into tube 4; 17, the gas-ajutages in burner 16, the same being arranged in spiral form; 18, pipes for supplying gas to the burner, the 70 same to be supplied with suitable valves, &c., usual in connection with gas-burners employed for the development of heat; 19, a crown-piece capping the upper end of the jacket; 20, outlet for waste products of combustion, the same being formed in crown-piece 19 and adapted for connection with a suitable waste-pipe, and 21 a bracket engaging the structure and adapted for use in supporting it independent of its base if such 75 system of support be preferred.

The water entering at 9 traverses the hollow 5 of the thread and leaves at pipe 8. The hot products from ring-burner 15 traverse the spiral passage 12 and leave at the top of 85 the jacket, going thence to the waste-pipe, these hot products imparting heat to the spirally-moving current of water through the metallic walls of the thread. At the same time tubular burner 16 imparts heat to the 90 water through the metal of tube 4.

The presence of space 7, formed by keeping the general interior surface of the body of the screw a little distance away from the exterior of tube 4, results in a thin body of 95 water being subjected to the action of heat transmitted through the metal, thus enhancing the rapidity with which the heat is transmitted to the water.

The spiral disposition of gas-ajutages 17 100 in the tubular burner 16 guards against the air-supply to one ajutage, being compelled

to pass directly up through the gas burning at the ajutage immediately below, and thus avoids the incomplete combustion and the odors found to be incident to all other disposition of the ajutages 17 with which I have experimented.

Tube 4 is, when broadly considered, merely a core to provide an inner wall for the hollow 5 of the screw-thread, but it has in addition 10 important advantages in a structural way. It would be extremely difficult if not impossible to cast the hollow of thread 5 if tube 4 were an integral part of the screw-casting. Especially would trouble arise if an attempt 15 were made to obtain the thin space 7. The employment of the separable screw - core formed by the tube 4 permits of casting the screw with its hollow threads on a substantial sand core, and the presence of rib 6, incidental to the formation of space 7, permits of the exterior of the tube engaging only the narrow surface formed by the rib, thus avoiding difficulties which might arise in fitting; but I should here explain that in practice I 25 do not find it important to secure a water-tight juncture between the exterior of tube 4 and the surface of rib 6, an ordinary rough fit being all-sufficient, and any slight leakage which may occur past rib 6 not materially interfering with the general spirality of the current of water flowing through the heater. It 30 will be understood, of course, that the screw-core formed by tube 4 has a tubular form only as incidental to the desire to employ 35 heat within the interior of the screw.

The jacket need fit the exterior of the screw-threads with but ordinary nicety, any slight leakage of the hot gases past the screw-threads not materially detracting from the 40 general spirality of the course of the gases.

I claim as my invention—

1. In a water-heater, the combination, substantially as set forth, of a vertically-disposed screw having a tight spiral water-passage, 45 water connections to and from said passage, a jacket closely surrounding said screw and forming a spiral air - passage between the threads of said screw open at its upper and lower ends, and a gas-burner disposed below 50 the open lower end of said spiral air-passage.

2. In a water-heater, the combination, substantially as set forth, of a vertically-disposed screw having a tight spiral water-passage and having also an open axial air-passage through

it, water connections to and from said spiral 55 water - passage, a jacket surrounding said screw and forming a spiral air-passage between the threads of the screw open at its upper and lower ends, and a gas-burner at the base of said screw and discharging its products to the base of said spiral air-passage.

3. In a water-heater, the combination, substantially as set forth, of a metallic screw having a hollow thread and having spirally-arranged thin spaces 7 communicating with and 60 forming an expansion of the base of the hollow of the thread, water connections to and from the passage formed by the hollow of the thread, and means for applying heat to said screw.

4. In a water-heater, the combination, substantially as set forth, of a vertical screw having a spiral water-passage and having an axial air-passage, water connections to and from said spiral passage, and a tubular burner disposed within said axial air-passage and having 75 gas-ajutages in its periphery.

5. In a water-heater, the combination, substantially as set forth, of a vertical screw having a spiral water-passage and having an axial air-passage, water connections to and from said spiral passage, and a tubular burner disposed within said axial air-passage and having a spiral series of gas-ajutages in its periphery.

6. In a water-heater, the combination, substantially as set forth, of a vertical screw having a hollow body and thread, a spiral rib 6 projecting from the inner wall of said body, a cylindrical core disposed within said body, 90 and having its periphery engaging said spiral ribs, water connections to and from the spiral passage formed by the hollow thread of the screw, and a gas-burner at the base of the screw.

7. In a water-heater, the combination, substantially as set forth, of a vertical screw having a hollow body and thread, a tubular cylindrical core disposed within the body of the screw and having its exterior in water-tight 100 connection with the interior of the ends of the screw-body, and a gas-burner at the base of the screw.

P. G. VAN WIE.
